(57) **CLAIM**

The ornamental design for a double-sided tangential cutting insert, as shown and described.

DESCRIPTION

FIG. 1 is an isometric view of the double-sided tangential cutting insert showing our new design in accordance with an aspect of the invention;

FIG. 2 is a front view of the double-sided tangential cutting insert of FIG. 1;

FIG. 3 is a rear view of the double-sided tangential cutting insert of FIG. 1;

FIG. 4 is a right side view of the double-sided tangential cutting insert of FIG. 1;

FIG. 5 is a left side view of the double-sided tangential cutting insert of FIG. 1;

FIG. 6 is a top view of the double-sided tangential cutting insert of FIG. 1; and,

FIG. 7 is a bottom view of the double-sided tangential cutting insert of FIG. 1.
